UNITED STATES PATENT OFFICE.

THOMAS P. HAMILTON, OF CHICAGO, ILLINOIS, ASSIGNOR TO BAUER & BLACK, OF CHICAGO, ILLINOIS, A CORPORATION OF ILLINOIS.

SURGICAL SWAB.

1,229,195.

Specification of Letters Patent.

Patented June 5, 1917.

Application filed September 9, 1916. Serial No. 119,190.

To all whom it may concern:

Be it known that I, THOMAS P. HAMILTON, a citizen of the United States, residing at Chicago, in the county of Cook and State 5 of Illinois, have invented certain new and useful Improvements in Surgical Swabs, of which the following is a specification.

This invention relates to a surgical swab and has for its object the provision of a 10 simple means for transporting small quantities of a cleansing, antiseptic or healing liquid in a manner best adapted to render it quickly available and readily applicable when needed.

15 Further objects and advantages of my invention will be apparent as it is better understood by reference to the following specification when read in connection with the accompanying drawing illustrating the preferred embodiment thereof, in which—

Figure 1 is a side elevation of a complete swab according to my invention;

Fig. 2 is a longitudinal section through the swab;

25 Fig. 3 is an elevation partially in section of the tubular fabric which surrounds and incloses the liquid container, and

Fig. 4 is a transverse section on the line 4—4 of Fig. 3.

30 Referring to the drawing, 1 indicates an elongated sealed container of glass or other readily friable material adapted to contain a quantity of liquid 2. In sealing the container 1 I provide a constricted portion or 35 neck 3 projecting from one end thereof, the purpose of which will hereafter more fully appear.

The container 1 is completely inclosed within a wrapper 4 consisting of tubular 40 fabric, the inner diameter of which corresponds closely to the outer diameter of the container 1. The tubular fabric is braided, knitted or woven and is raveled at one end 5. It is slipped over the container 1 with 45 the raveled end 5 adjacent the constricted portion or neck 3 and is fastened, preferably by means of a cord 6, beyond the neck 3 to retain the neck 3 within the wrapper 4 when the former is broken. The raveled end 5 of the wrapper 4 forms a brush or applicator for the liquid. The wrapper 4 except for the portion beyond the neck 3 is 50 impregnated with a liquid resisting material, preferably paraffin and beeswax the 55 free end 7 of the wrapper 4 being folded

over the rounded end of the container 1 in which position it is retained by the impregnating material.

To utilize my invention it is necessary merely to break the neck 3 of the container 1 whereupon the liquid is allowed to flow to the applicator. The liquid is readily applied by grasping the impregnated wrapper 4 about the container 1 which does not absorb any of the liquid. When the contents of the container has been utilized the swab is discarded. During the application of the liquid the broken end of the receptacle 1 is retained by the cord 6 and can not escape to the wound being treated.

70 My invention is particularly desirable as a means for transporting and applying iodin to wounds since small but efficient quantities of iodin may be readily carried by individuals in a form which makes it quickly 75 available and readily applicable when needed. My invention, as will be apparent, is equally efficient as a means for transporting and applying liquids other than iodin and I do not desire to be limited to a means 80 adapted only to contain iodin. The tubular wrapper forms a smooth and regular sheath of practically uniform thickness inclosing the container and besides presenting a neat and attractive appearance it insures 85 substantial uniformity of size and shape of the swabs. The container can readily be inserted in the sheath and it is only necessary to tie the brush end and seal the other end 90 thereof to wholly inclose and protect the container.

95 It will be readily understood that various changes may be made in the form, construction and arrangement of the parts without departing from the spirit and scope of the invention or sacrificing any of its material advantages, the form hereinbefore described being merely a preferred embodiment thereof.

I claim:

100 1. A surgical swab comprising an elongated friable liquid container, and a tubular circumferentially continuous textile sheath fabricated to receive and snugly inclose said container, said sheath extending beyond one end of the container to form a brush.

105 2. A surgical swab comprising an elongated friable liquid container, a tubular circumferentially continuous textile sheath 110

fabricated to receive and snugly inclose said container, said sheath extending beyond one end of the container and raveled to form a brush.

5. 3. A surgical swab comprising an elongated friable liquid container, a tubular textile sheath fabricated to receive and snugly inclose said container, said sheath extending beyond one end of the container and

raveled to form a brush, the opposite end of 10 the sheath being sealed and the whole sheath, except the brush, being impregnated with a liquid resistant material.

THOMAS P. HAMILTON.
